CLAIM

The ornamental design for a drift cart, as shown and described.

DESCRIPTION

The patent or application file contains at least one drawing executed in color. Copies of this patent or patent application publication with color drawing(s) will be provided by the Office upon request and payment of the necessary fee.

1. Drift cart
2. Drift cart
3. Drift cart
4. Drift cart
5. Drift cart
6. Drift cart
7. Drift cart
- 1.1 : Front
- 1.2 : Back
- 1.3 : Left
- 1.4 : Right
- 1.5 : Top
- 1.6 : Bottom
- 1.7 : First perspective view
- 1.8 : Second perspective view
- 2.1 : Front
- 2.2 : Back
- 2.3 : Left
- 2.4 : Right
- 2.5 : Top
- 2.6 : Bottom
- 2.7 : First perspective view
- 2.8 : Second perspective view
- 3.1 : Front
- 3.2 : Back
- 3.3 : Left
- 3.4 : Right
- 3.5 : Top
- 3.6 : Bottom
- 3.7 : First perspective view
- 3.8 : Second perspective view
- 4.1 : Front
- 4.2 : Back
